UNITED STATES PATENT OFFICE.

CLAUDE F. JONES, OF DILL, OKLAHOMA.

FIRE-EXTINGUISHER.

1,368,159.

Specification of Letters Patent.

Patented Feb. 8, 1921.

Application filed April 24, 1918. Serial No. 230,466.

To all whom it may concern:

Be it known that I, CLAUDE F. JONES, a citizen of the United States, residing at Dill city, in the county of Washita, State of Oklahoma, have invented certain new and useful Improvements in Fire-Extinguishers; and I do hereby declare the following to be a full, clear, and exact description of the invention, such as will enable others skilled in the art to which it appertains to make and use the same.

This invention relates to new and useful improvements in fire-extinguishers, and particularly to devices of this character for extinguishing fires in cotton gins.

One object of the present invention is to provide a novel and improved device whereby the gin man can quickly and easily start the feed water pump of the steam boilers in the engine room, without the necessity of notifying the engineer and asking his assistance.

Another object is to provide a novel and improved device of this character whereby hot water can be directed on the burning cotton to extinguish the fire, this being more effective than cold water.

A further object is to provide a novel and improved controlling valve which simultaneously permits steam from the boiler to enter the steam cylinder of the pump and water to be pumped through the usual feed water heater to the gin room where the fire is located instead of to the boiler.

Other objects and advantages will be apparent from the following description when taken in connection with the accompanying drawing.

In the drawing:

Figure 1 is an elevation of my improved fire extinguisher for cotton gins.

Fig. 2 is a top plan view of the same.

Fig. 3 is an enlarged vertical sectional view through the controlling valve.

Fig. 4 is an enlarged vertical sectional view through the check valve.

Referring particularly to the accompanying drawing, 10 represents the water cylinder and 11 the steam cylinder of a pump. The pump is located adjacent the boiler 12, a steam conveying pipe 13 being connected to the boiler and to the said steam cylinder for delivering steam to said cylinder to actuate the pump. A yoke-shaped branch pipe 14 is connected at its ends with the steam

pipe 13. A tapering valve casing 16 is mounted above the pump and in this casing are the upper ports 17 and 18, and the diametrically opposite ports 19 and 20. Rotatable within the casing is a tapering valve 60 plug 21 which is formed with two transverse ports 22 and 23 which are arranged to register respectively with the ports 17 and 18 and the ports 19 and 20. The intermediate portion of the yoke 14 is connected to the 65 valve casing at the ports 18 and 20 so that steam from one arm of the yoke will be permitted to flow through the port 23 and into the other arm of the yoke, and thence to the steam cylinder of the pump. Connected with 70 the boiler and with the water cylinder of the pump is a pipe 24 which conveys hot water to the boiler from the pump, the latter drawing it from a feed water heater as indicated. In this pipe 24 there is interposed a valve 75 casing 25, and in said casing is mounted a check valve 26 for preventing back pressure from the boiler. Connected to the pipe 24, and to the casing 16, at the port 19, is a pipe 27. Connected to the casing 16, at the port 80 17, is a branch pipe 28 which leads to the gin room, where it is connected to a hose (not shown), for use by the operator in directing water on the burning cotton.

The larger end of the valve casing 16 has 85 screwed thereon a cap 30 for retaining the valve therewithin. The other, or smaller end of the valve is formed with a reduced stem extension 31 which projects through the smaller end of the casing, and is formed 90 with a rectangular portion 32 for the reception of the radial crank arm 33. The smaller end of the casing 16 is externally threaded to receive thereon the threaded cap 34 and through which the said extension or stem 95 31 projects. Encircling the stem 31 between the cap and the crank arm 33, is a coil spring 35 which serves to draw the valve into firm frictional contact with the interior face or bore of the casing whereby a watertight and 100 steamtight joint is provided.

In the steam pipe 13, between the arms of the yoke or branch 14, there is disposed the controlling valve 15, by means of which steam can be permitted to pass directly from 105 the boiler to the engine cylinder when the engineer desires to replenish the water in the boiler.

From the foregoing it will be apparent that when a fire occurs in the gin room the oper- 110

ator there has only to pull the operating rod 36, which is connected to the outer end of the crank arm 33, to open the valve 21, and permit steam from the boiler to pass to the engine cylinder. This will result in the immediate starting up of the pump, with the consequent pumping of hot water from the heater through the valve 21 and pipe 28 to the gin room, where the operator can 10 direct the hose to quickly apply the water to the burning cotton. Thus the necessity of sending word or signaling to the engineer to start the pump, is obviated, and the application of water to the fire greatly facilitated.

Whenever the pump is running it puts pressure on the water in the pipe 24, and when such pressure exceeds that within the boiler the check valve 26 will open and the water will flow into the boiler as usual. Under ordinary circumstances the engineer starts the pump by opening valve 15, closing it again when the water in the boiler has been replenished. But when a fire occurs and 25 a distant operator opens the double valve by pulling on the rod or wire 36 and starting the pump as above described, the water will flow through the branch pipe 28 rather than toward the boiler because when the latter occurs it would meet with resistance. The

check valve will remain closed until the pressure in the boiler again falls, and therefore the delivery of water through the branch pipe will not reduce the boiler pressure which might result in retarding or checking 35 the action of the pump. The advantage of using hot water to extinguish fires in cotton mills is well known to those of experience.

What is claimed is:

In a fire extinguisher for cotton gins, the 40 combination with a boiler, a steam driven pump, a steam supply pipe from the boiler to the pump, a pipe feeding hot water to the pump and from the pump to the boiler, and a check valve in this pipe opening toward 45 the boiler; of a branch pipe leading from the water pipe between the pump and check valve to the gin room, an engineer's valve in said steam supply pipe, a branch steam pipe leading around this valve, a single 50 valve for controlling both branch pipes, and means for operating this valve from said gin room.

In testimony whereof, I affix my signature, in the presence of two witnesses.

CLAUDE F. JONES.
